UNITED STATES PATENT OFFICE

150,002

DESIGN FOR A FILM SPLICER OR THE LIKE

Ben Eisenberg, Larchmont, and Otto B. Schwarz,
New York, N. Y., assignors to Lektra Laboratories, Inc., a corporation of New York

Application April 1, 1947, Serial No. 138,080

Term of patent 7 years

(Cl. D61—1)

To all whom it may concern:

Be it known that we, Ben Eisenberg and Otto B. Schwarz, both citizens of the United States of America, residing respectively at Larchmont, in the county of Westchester and at New York city, in the county of New York, both being in the State of New York, have invented a new, original, and ornamental Design for Film Splicers or the like, of which the following is a specification, reference being had to the accompanying drawings, forming part thereof, in which

Figure 1 is a perspective view of a film splicer in the open position, showing our new design;

Figure 2 is a perspective view of said film splicer in the closed position;

Figure 3 is a side elevational view of said film splicer; and

Figure 4 is a top plan view of said film splicer.
We claim:

The ornamental design for a film splicer or the like, as shown.

BEN EISENBERG.
OTTO B. SCHWARZ.
